THE MORRIS PETERS CO. - PHOTO-LITHO - WASHINGTON, D. C.

UNITED STATES PATENT OFFICE.

CHARLES C. WORTHINGTON, OF IRVINGTON, NEW YORK.

VALVE-MOVEMENT FOR STEAM-ENGINES.

SPECIFICATION forming part of Letters Patent No. 695,021, dated March 11, 1902.

Application filed July 26, 1897. Serial No. 645,905. (No model.)

To all whom it may concern:

Be it known that I, CHARLES C. WORTHINGTON, a citizen of the United States, residing at Irvington, county of Westchester, and 5 State of New York, have invented certain new and useful Improvements in Valve-Movements for Steam-Engines, fully described and represented in the following specification and the accompanying drawings, forming a part of 10 the same.

The object of the present invention is to provide an improved valve-movement for steam and other expansion engines of that general class in which a single valve controls the admission and cut-off of the motor fluid at each 15 end of the steam-cylinder, and, further, to provide an improved valve-movement for such duplex and other multiple cylinder direct-acting engines by which the valves of 20 each cylinder shall be actuated to cut off the motor fluid by the piston of their own cylinder and shall be actuated for the admission of motor fluid and released for the cut-off movement by the piston of another cylinder. 25 While, however, my improved valve-movement is applicable to duplex and other multiple cylinder direct-acting engines, it may be applied likewise to single or multiple cylinder crank-engines of various classes with the 30 valve-movement actuated for opening and closing the valves by eccentrics or other suitable means.

As a full understanding of the invention can best be given by a detailed description of 35 a construction embodying the same, such a description will now be given in connection with the accompanying drawings, forming a part of this specification, and showing the movement applied in its preferred forms to a 40 duplex direct-acting pumping-engine of the class now well-known as "duplex pumps" and to a single-crank pump, and certain modifications in the application of the invention and the features forming the invention will 45 then be specifically pointed out in the claims.

In the drawings, Figure 1 is a side elevation of a duplex pump provided with the improved valve-movement in its preferred form. Fig. 2 is a plan view of the same. Figs. 3, 4, and 50 5 are diagrammatic side elevations of the steam end on one side with the respective pistons shown in light and heavy dotted lines,

and showing the parts in different positions. Figs. 6 and 6^a are detail views showing the parts of the valve-movement at the opposite 55 ends of the cylinder shown in Figs. 3, 4, and 5 and in the position illustrated in Fig. 5. Fig. 7 is an enlarged side view of the valve-movement at the left end of the cylinder shown in Fig. 5, with parts broken away to 60 show the construction. Fig. 8 is an enlarged edge view of the same valve-movement looking to the right in Fig. 5. Fig. 9 is a similar view of the valve-movement looking in the opposite direction to Fig. 7 or to the left in 65 Fig. 5. Fig. 10 is a detail section on the line 10 of Figs. 8 and 9. Fig. 11 is a side view looking to the right in Fig. 12, showing a construction by which the valve is actuated for cut-off by the opposite side in case of 70 accident to the cut-off connections or may be run without cut-off. Fig. 12 is an edge view looking to the left in Fig. 11. Fig. 13 is a side elevation of the steam end of a duplex engine, showing a construction in which 75 the admission and exhaust valves are operated from a single rocker. Fig. 14 is a similar view of a crank and fly-wheel engine with the valve-movement actuated for admission and cut-off by separate eccentrics on the 80 crank-shaft and the cut-off controlled by a governor. Figs. 15 to 20 show a slightly-modified construction in which the member actuating the valves for cut-off has a straight-line movement. Figs. 15 and 16 are side 85 views corresponding to Figs. 3 and 4 and showing the same positions of the parts, the valves and pistons being projected above the cylinders to show their positions. Fig. 17 is a side elevation of the valve-movement at the right 90 end of the cylinder, partly in section to show the construction. Fig. 18 is a view on the line 18 of Fig. 17 looking to the left. Fig. 19 is a section on the line 19 of Fig. 18 looking to the left. Fig. 20 is a plan view of Fig. 17. 95

Referring now especially to the construction shown in Figs. 1 to 10, the engine shown is, as to general construction, a single-expansion duplex direct-acting pump having steam-cylinders A A' and water-cylinders B B' on 100 opposite sides of the pump, with steam-pistons a a' connected to the plungers of the water-cylinders by piston-rods b b'. The steam-cylinders are supplied with steam through

- valve-chests at the top of the cylinders by induction-pipe C and exhaust through valve-chambers at the bottom of the cylinder and exhaust-pipe D. The pump has compensating cylinders E, which may be of any approved form and supplied with fluid in any suitable manner, and these cylinders may be connected to the piston cross-heads c, as shown, or connected otherwise, so as to act 10 with and against the pistons, as usual. The steam-cylinders have the admission-ports 1 at the top of the cylinder and exhaust-ports 2 at the bottom of the cylinder, the admission-ports being controlled by oscillating valves d and the exhaust-ports by oscillating valves e, separate admission and exhaust valves thus being used, as is preferable, at opposite ends of each cylinder and a single valve at each end of the cylinder controlling 20 both the admission and cut-off. The valves d on each side of the engine are operated for the admission of steam by the opposite side of the engine and are operated for the cut-off by the same side of the engine.
- 25 The valves d are thus operated in the construction shown by the following mechanism: Each valve-stem 10 of these oscillating valves has rigidly secured thereto or formed therewith a crank shown as formed by a sleeve f, 30 which constitutes a crank-disk and is provided on one side with a circumferential groove 11, terminating in a shoulder 3, and with a projecting lug 12. Outside the crank f is mounted loosely upon the valve-stem 10 a sleeve g, having a crank-arm 13, carrying an inwardly-projecting stud 14, upon which stud is a spring-pressed catch 15, which is positioned to move in the groove 11 in the crank f and engage the shoulder 3 to actuate the 35 valve for the admission of steam, and this catch carries on the inner side of the catch-point a block 4, positioned to move inside the crank f. Inside the crank f is mounted another sleeve h, having a crank-arm 16, a circumferential cam-groove 5, arranged in line 40 with the block 4, so that the block is in the groove during a part of the movement of the sleeve g, and a lug 17, positioned to engage the lug 12 to rotate the crank f and oscillate 45 the valve for cut-off. By this construction the crank f, carrying the valve-stem, is rotated in one direction by the sleeve g through the engagement of catch 15 with shoulder 3 for the operation of the valve for admission 50 of steam. The catch 15 is then thrown out of engagement with the shoulder 3 by block 4 coating with the end of cam-groove 5 in sleeve h, so as to permit the return of the crank f, and the crank f is returned by the sleeve h 55 for the operation of the valve for cut-off through the engagement of lug 17 on sleeve h with lug 12 on the crank f, as will be fully described hereinafter in connection with the operation of the engine.
- 60 The connections for operating the sleeve g, which may be called the "admission-sleeve," and the sleeve h, which may be called the

"cut-off" sleeve, from the respective pistons are as follows: The two crank-arms 13 on the admission-sleeves of each cylinder are connected together by a link 18 and by link 19, connected to a crank-arm 20 to one of two crossover-shafts i, which are operated from the opposite sides of the engine by levers k, connected by links 21 to the cross-heads c, 75 the crank-arms 13 on each side of the engine thus being connected to the crossover-shaft i, which is operated from the opposite side of the engine.

80 Mounted upon the side of each steam-cylinder is a rocker l, connected by links 22 to the crank-arms 16 on the cut-off sleeves h at the opposite ends of the cylinders, these links 22 preferably being made adjustable in length, as shown in Figs. 3, 4, and 5, so as to secure cut-off at the desired point in the stroke. Each of the rockers l is connected by a link 23 to a crank-arm 24 on the crossover-shaft i, which is operated from the same side of the engine, so that each rocker l and the cut-off 90 sleeves h are operated from the piston of their own cylinder—that is, from the same side of the engine.

95 The exhaust-valves e of each cylinder may be operated from the opposite side of the engine by any suitable connections, the stems of these valves being shown as carrying crank-arms 25, connected together by links 26 and connected by link 27 to a crank-arm 28 on rock-shaft 29, having a crank-arm 30, connected by link 31 to a crank 32 on the shaft i operated from the opposite side of the engine.

105 The operation of the construction above described will be understood from the drawings, especially Figs. 3 to 10, showing the cylinder A with its valves in three different positions, in connection with a brief description.

110 As shown in Fig. 3, piston a has just begun its stroke to the left, the admission-valves d at the right end of the cylinder having been opened for the admission of steam and the exhaust-valves e properly shifted by the piston a' on the opposite side of the engine, the 115 piston a' being now at about two-thirds stroke and both the pistons moving to the left, as indicated by the arrows. As the piston a moves to the left from the position shown in Fig. 3 the lower or actuating arm of rocker l, connected to the link 23, is moved to the left in that figure by the connection of this link to the crank-arm 24 on the shaft i, which is operated from and moving in the same direction as the piston of cylinder A, and through 120 the link 22 the crank-arm 16 on cut-off sleeve h at the right end of the cylinder is thus moved to the right, and by the engagement of the lug 17 on sleeve h with lug 12 on the crank f oscillates the valve to the right, the 125 catch 15 on sleeve g having been thrown out of engagement with shoulder 3 at the end of slot 11 on crank f by the engagement of the block 4 with the end of the cam-groove 5 in

the sleeve *h*, and as the piston *a* reaches the point of cut-off, which is shown in the drawings as about half-stroke, the valve *d* is thus oscillated sufficiently to cut off the steam from behind the piston, the parts then being in the position shown in Fig. 4 with the piston *a'* at the end of its stroke and about to move to the right on the shifting of the valves in cylinder A' by the piston *a*. As will be seen from a comparison of Figs. 3 and 4, this movement of the rocker *l* does not change the position of the sleeve *g* at the left end of the cylinder A, the arm of the rocker *l* which is connected to the crank-arm 16 of that sleeve swinging in such an arc as to produce this result. As will be seen from a comparison of these figures, also, the piston *a'* thus finishes its stroke to the left from the position shown in Fig. 3 to that shown in Fig. 4 without action upon either of the valves *d* of cylinder A, although the sleeves *g* are thus rotated to the right, as the catch 15 at the right end of the cylinder has been thrown out of the groove 11 and moves freely over the outer surface of the crank *f*, and the catch 15 at the left end of the cylinder is simply drawn backward in the groove 11 of the crank *f* without moving the latter. As the piston *a* continues its stroke from the position shown in Fig. 4, it shifts the valves *d* and *e* on cylinder A' for the reversal of the piston *a'* and completes its stroke without further control of the steam through either of the valves *d* of cylinder A, the arm of rocker *l*, connected by link 22 to the crank-arm 16 on sleeve *h* at the right end of the cylinder A, now moving in such an arc as to move the crank-arm but very little, and the movement of the cut-off sleeve *h* at the left end of the cylinder A by crank-arm 16, link 22, and the other arm of rocker *l* being in the same direction as and moving with the crank *f* as the latter is moved by the admission-sleeve *g*, actuated by piston *a'* for opening the valve *d* at the left end of the cylinder A. In the shifting of the valve *d* at the left end of the cylinder A by the piston *a'* for the reversal of the piston *a* the catch on crank-arm 13, carried by the sleeve *g*, engages the shoulder 3 when the catch 15 is moved from the position shown in Fig. 4 to the end of the groove 11, and the crank *f* and valve-stem of this valve are then rotated to the left in the figures from the position shown in Fig. 4 to that shown in Fig. 5, so as to open the valve at the left end of the cylinder A for the admission of steam. This movement of the piston *a'* does not affect the position of the valve *d* at the right end of cylinder A, as the catch 15, carried by sleeve *g* at the right end of the cylinder, is then simply moved backward over the crank *f* and in the groove 11 therein. As the piston *a'* in cylinder A' opens the admission-valve *d* at the left end of the cylinder A it also reverses the exhaust-valves *e* on cylinder A for the next stroke of the piston through the connections previously described. All the parts are now in the position shown in Fig. 5, with the pistons *a a'* both moving to the right. As the piston *a* in cylinder A moves to the right from the position shown in Fig. 5 it shifts the valve *d* at the left end of the cylinder to the left, so as to close port 1 and cut off the steam by moving the lower arm of the rocker *l* to the right, and thus through the link 22 and crank 16 rocking the cut-off sleeve *h* to the left in that figure, with the lug 17 on sleeve *h* engaging lug 12 on the crank *f* on the valve-stem, this movement being permitted by the throwing out of catch 15 on crank-arm 13 from groove 11 in the valve-stem by the engagement of block 4 with the end of cam-groove 5 in sleeve *h*. This movement of the rocker *l* does not change the position of the crank-arm 16 and cut-off sleeve *h* at the opposite end of the cylinder sufficiently to affect the control of the steam at this end. When the piston *a* has thus reached half-stroke, the steam is cut off and the parts again correspond in position to the showing in Fig. 4, except that the valves at the opposite ends of the cylinder are reversed in position. The cycle of operations from this point is the same as previously described, but with the piston *a* moving in the opposite direction. 95

In the duplex-pump construction shown and above described it will be seen that the catch 15, operating the valve for admission, has a considerable movement after operating the valve and being thrown out of position to engage shoulder 3 and has a considerable movement also before commencing to operate the valve by engagement of the shoulder 3. This feature is important in such duplex direct-acting engines in which the length of the stroke is variable, and the admission member of the valve-movement actuates the valve during the middle part of the stroke of the piston on the opposite side and with lost motion at both ends of the stroke. It will be understood, however, that when this valve-movement is applied to an engine having a fixed length of stroke—as, for instance, a crank and fly-wheel engine—this lost motion is not required, and it will probably be found preferable to arrange the parts so that the catch 15 has no substantial movement on either side of the shoulder 3, but is simply thrown out at the proper time to permit the return of the valve, and when withdrawn for the next operation of the valve only passes the shoulder so as to drop into position to engage the latter. 100

In Figs. 11 and 12 I have shown in detail and indicated in dotted lines in Figs. 6 and 6^a a feature which is preferably employed in all cases, but may be omitted, and is not shown in the other figures in order to more clearly illustrate the rest of the parts. This feature consists in providing means by which the valves *d* will be closed by the admission-sleeves *g* in case of accident to the cut-off connections or their failure to work for any reason and by which the engine may be run low-

duty when desired—that is, without cut-off and admitting steam throughout the stroke. This result is secured in the construction shown by a lug 50 on the admission-sleeve *g*, 5 positioned to engage a lug 51 on the crank *f*, so as to move the valve *d* into position to close the admission-port on the return movement of the admission-sleeve in case the cut-off connections fail to act. In such case the 10 admission-sleeve, after the catch 15 has been thrown out by the block 4 and cam-surface 5, moves onward with the catch on the outer surface of the crank *f* until the stroke of piston *a'* is completed from the position shown 15 in Fig. 5 and on the return movement of the admission-sleeve actuated by the piston *a'* on its next stroke the lug 50 engages the lug 51 if the cut-off connections fail to act and closes the valve *d*, this admission-sleeve thus actuating 20 the valves *d* in both directions.

If the engine is to be run low duty—that is, without the cut-off and admitting steam throughout the stroke—this result may readily be secured by simply detaching the cut-off 25 rockers *l* from the pistons, so that they will not be operated thereby and securing them in fixed positions, such that the sleeves *h* are held with the cam-grooves 5 in position to throw out the catches 15 at the proper time, 30 in which position the lugs 17 will be out of the path of lugs 12, so as not to interfere with the movement of the valves, the admission-sleeves *g* then acting to open one valve *d* by the catch 15 engaging shoulder 3 and to close 35 the other valve *d* by the engagement of lug 50 with lug 51. In the construction shown and described above this position of the rocker *l* is shown in dotted lines, the link 23 being shown in dotted lines as detached from the 40 crank-arm 24 and secured to the engine-cradle below the piston-rod to hold the rocker *l* stationary in the proper position.

In Fig. 13 I have shown a slightly-modified construction in which the valves *d* are operated for the admission of steam by a wrist-plate *m*, connected to the crank-arms 13 of sleeve *g* by link 33, and which wrist-plate operates also the exhaust-valves *e*, being connected to the crank-arms 25 by links 34. The 45 wrist-plate *m* is connected to the shaft *i*, actuated from the opposite side of the engine, by the link 35, corresponding to the link 19 of the construction previously described. In this modified construction the wrist-plate *m*, 50 actuating the valves *d* for admission, is below the rocker *l*, by which these valves are actuated for cut-off, so that for convenience the crank-arms 13 are below the valves and the crank-arms 16 above, the rocker *l* being connected to the crank-arms 16 by links 22 and 55 to the crank-arm 20 on shaft *i*, actuated from the same side of the engine, by link 19, as in the construction previously described. The construction and operation of the sleeves *fgh* 60 and their parts is the same as previously described and will be understood without further description.

In Fig. 14 I have shown a single-crank and fly-wheel engine with my improved valve-movement applied thereto, as in the construction shown in Fig. 13, except that the arrangement of the sleeves and crank-arms is varied slightly and the rocker *l* is made adjustable and controlled by a governor, so as to automatically vary the point of cut-off in 70 accordance with the speed of the engine. In this construction the rocker *l* and wrist-plate *m* are connected, respectively, by eccentric-rods 36 37 to eccentrics *n o* on the crank-shaft *F*, carrying the fly-wheel *G* and actuated from 75 the piston-rod *p* through crank 38 and link *q*. The rocker *l* is pivoted on a block 39, mounted to slide vertically in guides 6 on the valve-chamber and connected by link 7 to a vertically-oscillating bell-crank lever 8, connected 80 by a link 40 to another bell-crank lever 9, which is actuated by a governor *H*, which may be of any suitable form and actuated from the engine in any common or suitable manner, the connections being such as to 85 lower the block 39 and secure an earlier cut-off in case the speed is excessive and to raise the block 39 and secure a later cut-off if the speed falls. The operation of this construction will be readily understood from the drawings without detailed description, the eccentric 37 operating the wrist-plate *m* so as to open the valves *d* at the top of the cylinder for the admission of steam and to open and close the exhaust-valves *e* at the bottom of 90 the cylinder, and the eccentric 38 through its link 36 operating the rocker *l*, so as to close the valves *d* and cut off the steam at the desired point, this point being controlled by the 95 governor through the sliding pivoted block 39 and connections shown and above described.

The invention may be embodied in constructions in which the parts differ widely in form and movement from those shown, and it will be understood that the invention is not to be limited to valves of the oscillating class illustrated or to valve-movements in which the valve-actuating parts move in curved paths. Thus it is obvious that the 100 oscillating crank-disks *f* of the construction shown or other suitable members having an oscillating movement, so as to form cranks actuated by the valve-movement and actuating the valves, may not be connected directly 105 to the valves, as shown, but may be connected to slide-valves or valves of any other movement by intermediate connections between the cranks and valves of form suitable to secure the desired movement, so that the devices shown may readily be applied to other 110 than oscillating valves.

The oscillating or curved movement of the parts of the valve-motion also may readily be varied to a straight-line movement, if desired, one or both of the admission and cut-off members having such straight-line movement. For the purpose of illustrating this 115 I have shown in Figs. 15 to 20 a construction

similar to that shown in Fig. 13, employing oscillating valves and a wrist-plate *m*, actuating said valves for admission, and separate exhaust-valves, but with the cut-off movement of the valves *d* secured by a straight-line movement of the cut-off members of the valve-motion instead of by the oscillating sleeves *h* of the constructions previously described. The same reference-letters are used in this construction for parts corresponding to those previously described, and only a description of those parts differing in form or arrangement from those previously described is necessary. In this construction blocks 4 on the spring - pressed catches 15 run in grooves 41 in the stationary bearing-sleeves *r* of the valve-stems, while the catches 15 are actuating the cranks *f* for the admission movement, and the catches are thrown out by the cam - surfaces at the end of these grooves, these fixed grooves and cams therefore taking the place of the cam-grooves 5 in sleeves *h* of the construction previously described. In place of the oscillating sleeves *h* having the projections 17, engaging the projections 12 on the cranks *f*, for the cut-off movement actuating members *s* are used, having a straight-line horizontal movement, these actuating members consisting of lugs depending from a sliding support on bar *t*, moving in guides 42 and actuated from the piston on the same side of the engine by connections similar to those previously described, the link 19 of the construction shown in Fig. 13 being connected to this sliding bar at any suitable point or connections of other suitable form being used. The lugs *s* are preferably made adjustable, so that the exact point of cut-off desired may be attained readily and with certainty. For this purpose any suitable construction may be used; but, as shown, the lugs *s* are mounted to slide in slotted holders 43 and adjustable longitudinally in these holders by screws 44, passing through the lugs; a clamping-nut and washer 45 being used to lock the lugs in adjusted position. The operation of this construction will be readily understood from Figs. 15 and 16, in connection with the previous full description of the operation of the construction shown in Figs. 1 to 10, the parts being shown in Fig. 15 with the piston *a* just starting upon its stroke to the left and the piston *a'* past half-stroke, moving in the opposite direction, and in Fig. 16 with the piston *a* advanced to about half-stroke and the piston *a'* at the end of its stroke. In the position shown in Figs. 15 and 17 to 20 the catch 15 on the sleeve *g* at the right end of cylinder A has just been actuated by the opposite side of the engine, through the rocker *l* and link 33, to open the valve *d* at the right end of the cylinder, and the catch is just about to be thrown out by the engagement of the block 4 with the cam-surface at the end of groove 41, and the lug *s* at the right end of the cylinder is in position to engage the lug 12 on crank *f* shortly

after the commencement of the stroke of piston *a* to the left, so as to return the crank *f* and valve-stem and cut off steam at the proper point, during which movement of the crank *f* and valve-stem the catch 15 is out of the groove 41 and riding on the outer surface of crank *f*. On the return movement of the piston on the next stroke the same operations occur at the left end of the cylinder, the catch 15 at the right end of the cylinder being meanwhile returned by the wrist-plate *m*, so as to drop into the groove 41 in position to engage the shoulder 3 as the block 4 passes off the cam-surface at the end of the groove, and the lug *s* at the right end of the cylinder being moved to the right to permit the next admission movement of the crank *f* and lug 12. It will be understood that valves of different form and motion from those shown may be used and many other modifications made in the constructions illustrated without departing from the invention and that I am not to be limited to the exact form or arrangement of the devices shown.

What I claim is—

1. The combination with an engine-cylinder and a valve controlling the admission and cut-off of the motor fluid, of devices connected to said valve for operating it for admission and disconnected from said valve to permit the return of the valve for cut-off, and means actuated by a moving part of the engine for operating said valve for cut-off, substantially as described. 95
2. The combination with an engine-cylinder and a valve controlling the admission and cut-off of the motor fluid, of devices connected to said valve for operating it for admission and disconnected from said valve to permit the return of the valve for cut-off, and connections for operating said valve for cut-off by the piston of said cylinder, substantially as described. 105
3. The combination with an engine-cylinder and a valve controlling the admission and cut-off of the motor fluid, of devices for operating said valve for admission having a catch connected to said valve during the admission movement and operated to release the valve for the return of the valve for cut-off, and connections for operating said valve for cut-off from a moving part of the engine, substantially as described. 115
4. The combination with an engine-cylinder and a valve controlling the admission and cut-off of the motor fluid, of a valve-actuating member having a catch for operating said valve for admission, means for tripping said catch to permit the return of the valve for cut-off, and a second valve-actuating member actuated by a moving part of the engine for operating said valve for cut-off, substantially as described. 125
5. The combination with an engine-cylinder and a valve controlling the admission and cut-off of the motor fluid, of a valve-actuating member having a catch for operating said

valve for admission, a second valve-actuating member for operating said valve for cut-off, and means carried by said second actuating member for tripping said catch to permit the return of the valve for cut-off, substantially as described.

6. The combination with an engine-cylinder and a valve controlling the admission and cut-off of the motor fluid, of a rocking valve-actuating member having a catch for operating said valve for admission, means for tripping said catch to permit the return of the valve for cut-off, and a second valve-actuating member actuated by a moving part of the engine for operating said valve for cut-off, substantially as described.

7. The combination with an engine-cylinder and a valve controlling the admission and cut-off of the motor fluid, of a rocking valve-actuating member having a catch for operating said valve for admission, means for tripping said catch to permit the return of the valve for cut-off, and a second rocking valve-actuating member actuated by a moving part of the engine for operating said valve for cut-off, substantially as described.

8. The combination with an engine-cylinder and a valve controlling the admission and cut-off of the motor fluid, of valve-actuating members for operating said valve in opposite directions for admission and cut-off, means for actuating the member that operates the valve for admission and disconnecting said member from the valve to permit the cut-off movement, and means for actuating the other member by a moving part of the engine for the cut-off movement, substantially as described.

9. The combination with an engine-cylinder and single valves controlling the admission and cut-off at opposite ends of the cylinder, of separate valve-actuating members for operating said valve in opposite directions for admission and cut-off, means for actuating the members that operate the valves for admission and disconnecting said members from the valves to permit the cut-off movement, and means for actuating the other members by a moving part of the engine for the cut-off movement, substantially as described.

10. The combination with an engine-cylinder and single valves controlling the admission and cut-off at opposite ends of the cylinder, of valve-actuating members for operating said valves in opposite directions for admission and cut-off, means for actuating the members that operate the valves for admission and disconnecting said members from the valves to permit the cut-off movement, means for actuating the other members by a moving part of the engine for the cut-off movement, and separate exhaust-valves and means for operating the same, substantially as described.

65 11. The combination with an engine-cylinder and a valve controlling the admission and

cut-off of the motor fluid, of devices connected to said valve for operating it for admission and disconnected from said valve to permit the return of the valve for cut-off, connections for operating said valve for cut-off from a moving part of the engine, and a separate exhaust-valve and means for operating the same, substantially as described.

75 12. The combination with two cylinders and single valves controlling the admission and cut-off of the motor fluid, of means for operating the valves of each cylinder for admission by the piston of the other cylinder and for cut-off by the piston of their own cylinder, and disconnecting said valves from one of said pistons for their movement by the other piston, substantially as described.

13. The combination with two cylinders and single valves controlling the admission and cut-off of the motor fluid, of means for operating the valves of each cylinder for admission by the piston of the other cylinder and disconnecting the valves from said pistons for the cut-off movement, and means for operating said valves for cut-off by the piston of their own cylinder, substantially as described.

14. The combination with two cylinders and single valves controlling the admission and cut-off of the motor fluid, of valve-actuating members having catches connected to said valves during the admission movement and operated to release the valves for the return of the valves for cut-off, connections for operating said actuating members to operate the valves of each cylinder for admission by the piston of the other cylinder, and means for operating said valves for cut-off by the piston of their own cylinder, substantially as described.

15. The combination with a plurality of engine-cylinders and single valves controlling the admission and cut-off of the motor fluid, of valve-actuating members having catches and connections for actuating said members to operate the valves of each cylinder for admission, means for tripping said catches to permit the return of the valves for cut-off, and other valve-actuating members and connections for operating said valves for cut-off, substantially as described.

16. The combination with a plurality of engine-cylinders and single valves controlling the admission and cut-off of the motor fluid, of valve-actuating members having catches and connections for actuating said members to operate the valves of each cylinder for admission, other valve-actuating members and connections for operating said valves for cut-off, and means carried by said other actuating members for tripping said catches to permit the return of the valves for cut-off, substantially as described.

17. The combination with a plurality of engine-cylinders and single valves controlling the admission and cut-off at opposite ends of each cylinder, of separate valve-actuating

members for operating said valves in opposite directions for admission and cut-off, means for actuating the members that operate the valves of each cylinder for admission and disconnecting said members from the valves to permit the cut-off movement, and means for actuating the other members to operate the valves for cut-off, substantially as described.

18. The combination with two engine-cylinders and single valves controlling the admission and cut-off of the motor fluid, of means for operating the valves of each cylinder for admission by the piston of the other cylinder and disconnecting the valves from said pistons for the cut-off movement, means for operating said valves for cut-off by the piston of their own cylinder, and separate exhaust-valves and means for operating the exhaust-valves of each cylinder by the piston of the other cylinder, substantially as described.

19. The combination with two engine-cylinders and single valves controlling the admission and cut-off of the motor fluid, of valve-actuating members having catches connected to said valves during the admission movement and operated to release the valves for the return of the valves for cut-off, connections for operating said actuating members to operate the valves of each cylinder for admission by the piston of the other cylinder, means for operating said valves for cut-off by the piston of their own cylinder, and separate exhaust-valves and means for operating the exhaust-valves of each cylinder by the piston of the other cylinder, substantially as described.

20. The combination with two engine-cylinders and single valves controlling the admission and cut-off at opposite ends of each cylinder, of separate valve-actuating members for operating said valves in opposite directions for admission and cut-off, means for actuating the members that operate the valves of each cylinder for admission by the piston of the other cylinder and disconnecting said members from the valves to permit the cut-off movement, and means for actuating the other members to operate the valves for cut-off by the piston of their own cylinder, and separate exhaust-valves and means for operating the exhaust-valves of each cylinder by the piston of the other cylinder, substantially as described.

21. The combination with two engine-cylinders and single valves controlling the admission and cut-off at opposite ends of each cylinder, of separate valve-actuating members for operating said valves in opposite directions for admission and cut-off, means for actuating the members that operate the valves of each cylinder for admission by the piston of the other cylinder and disconnecting said members from the valves to permit the cut-off movement, and means for actuating the other members to operate the valves of each cylinder for cut-off by the piston of their own cylinder, said other members being adapted

to be secured in a fixed position for the operation of the valves without cut-off, substantially as described.

22. The combination with two engine-cylinders and single valves controlling the admission and cut-off at opposite ends of each cylinder, of separate valve-actuating members for operating said valves in opposite directions for admission and cut-off, means for actuating the members that operate the valves of each cylinder for admission by the piston of the other cylinder and disconnecting said members from the valves to permit the cut-off movement, said members being adapted to close the valves on their return movement in case the valves are not closed by the members that operate the valves for cut-off, and means for actuating the other members to operate the valves of each cylinder for cut-off by the piston of their own cylinder, said other members being adapted to be secured in a fixed position for the operation of the valves without cut-off, substantially as described.

23. The combination with a plurality of engine-cylinders and single valves controlling the admission and cut-off at opposite ends of each cylinder, of separate valve-actuating members for operating said valves in opposite directions for admission and cut-off, means for actuating the members that operate the valves of each cylinder for admission and disconnecting said members from the valves to permit the cut-off movement, said members being adapted to close the valves on their return movement in case the valves are not closed by the members that operate the valves for cut-off, and means for actuating the other members to operate the valves of each cylinder for cut-off, substantially as described.

24. The combination with an engine-cylinder and a valve controlling the admission and cut-off of the motor fluid, of a valve-actuating member having a catch for operating said valve for admission, a second actuating member for operating said valve for cut-off, and means carried by said second actuating member for tripping said catch to permit the return of the valve for cut-off, said second actuating member being adapted to be secured in a fixed position for tripping said catch for the operation of the valve without cut-off, substantially as described.

25. The combination with an engine-cylinder and a valve controlling the admission and cut-off of the motor fluid, of devices for operating said valve for admission having a catch connected to said valve during the admission movement and operated to release the valve for the return of the valve for cut-off, said devices being constructed to close the valve on their return movement if not previously closed, and connections for operating said valves by the engine for cut-off, substantially as described.

26. The combination with an engine-cylinder and a valve controlling the admission and

cut-off of the motor fluid, of devices for operating said valve for admission having a catch connected to said valve during the admission movement and operated to release the valve 5 for the return of the valve for cut-off, said devices being constructed to close the valve on their return movement if not previously closed, and connections for operating said valves for cut-off, said connections being 10 adapted to be secured in a fixed position for the operation of the valve without cut-off, substantially as described.

27. The combination with a plurality of engine-cylinders and single valves controlling 15 the admission and cut-off of the motor fluid, of valve-actuating members and connections actuated by the engine for moving said valves in opposite directions for admission and cut-off and for closing said valves by the valve- 20 actuating members that operate the valves for admission in case the valves are not closed by the members that operate the valves for cut-off, substantially as described.

28. The combination with an engine-cylinder 25 and a valve controlling the admission and cut-off of the motor fluid, of valve-actuating members and connections actuated by the engine for moving said valve in opposite directions for admission and cut-off and for closing 30 the valve by the valve-actuating member that operates the valve for admission in case the valve is not closed by the member that operates the valve for cut-off, substantially as described.

35 29. The combination with two engine-cylinders and single valves controlling the admission and cut-off of the motor fluid, of means for operating the valves by the piston of their own cylinder for cut-off and by the piston of 40 the other cylinder for admission and for closing said valves by the piston of the other cylinder in case they are not closed by the piston of their own cylinder, substantially as described.

45 30. The combination with an engine-valve and a crank connected to said valve, of two reciprocating members actuated by a moving part of the engine for moving said crank in opposite directions, a catch through which one 50 of said members engages said crank, and means for tripping said catch for the return of the valve, substantially as described.

31. The combination with an engine-valve and a crank connected to said valve, of two 55 reciprocating members actuated by moving parts of the engine for moving said crank in opposite directions, a catch carried by one of said members for engaging said crank, and means for tripping said catch by the other 60 member for the return of the valve, substantially as described.

32. The combination with an engine-valve and a crank connected to said valve, of a member rocking concentrically with said crank 65 and engaging said crank through a catch, means for tripping said catch for the return of the valve, and means for actuating the crank

by a moving part of the engine to return the valve, substantially as described.

33. The combination with an engine-valve 70 and a crank connected to said valve, of two members rocking concentrically with said crank and acting to move the valve in opposite directions, one of said members engaging said crank through a catch, and means 75 for tripping said catch by the other member for the return of the valve, substantially as described.

34. The combination with an engine-valve 80 and a crank connected to said valve, of two members actuated by moving parts of the engine and rocking concentrically with said crank and acting to move the valve in opposite directions, one of said members engaging said crank through a catch, and a cam 85 carried by the other member for tripping said catch for the return of the valve by said other member, substantially as described.

35. The combination with an engine-valve 90 and a crank connected to said valve, of a reciprocating member for moving said crank in one direction, a catch through which one of said member engages said crank, means for tripping said catch for the return of the valve, a member for moving said crank to 95 return the valve, and rocker *l* linked to said last-mentioned member, and means for actuating said members by moving parts of the engine, substantially as described.

36. The combination with a cylinder and 100 separate valves at opposite ends of the cylinder, of cranks connected to said valves, reciprocating members actuated by moving parts of the engine for moving said cranks in one direction, catches through which said 105 reciprocating members engage said cranks, means for tripping said catches for the return of the valves, other members for moving said cranks to return the valves, and rocker *l* connected by links to said last-mentioned members, substantially as described.

37. The combination with a cylinder and 110 separate valves at opposite ends of the cylinder, of cranks connected to said valves, reciprocating members for moving said cranks 115 in one direction, catches through which said reciprocating members engage said cranks, means for tripping said catches for the return of the valves, other members for moving said cranks to return the valves, and rocker *l* connected by links to said last-mentioned members, said rocker *l* having a pivot adjustable 120 to vary the operation of the valves, substantially as described.

38. The combination with a valve and crank 125 *f* connected to said valve, of sleeve *g* having a catch engaging said crank to move the valve in one direction, and sleeve *h* engaging the crank to return the valve and having means for tripping the catch to permit the return of the valve, and means for actuating said sleeves by moving parts of the engine, substantially as described.

39. The combination with a valve, of crank

5 *f* connected to the valve, sleeve *g* having a catch engaging said crank to move the valve in one direction said sleeve carrying also means for engaging the crank on the return of the sleeve to close the valve, means for tripping the catch to permit the return of the valve, and sleeve *h* engaging the crank to return the valve, substantially as described.

10 40. The combination with a valve, of crank *f* connected to the valve and having shoulder 3 and lug 12, sleeve *g* having catch 15 engaging said shoulder to move the valve in one direction and sleeve *h* having lug 17 engaging lug 12 and cam 5 for tripping said catch 15 to permit the return of the valve, substantially as described.

15 41. The combination with a valve, of crank *f* connected to the valve and having shoulder 3, lug 12 and lug 51, sleeve *g* having catch 15 20 engaging said shoulder to move the valve in one direction and lug 50 engaging said lug 51 to move the valve in the opposite direction, and sleeve *h* having lug 17 engaging lug 12 and cam 5 for tripping said catch to permit 25 the return of the valve, substantially as described.

42. The combination with valves *d* at opposite ends of the cylinder, of cranks connected to the valves, sleeves *g* having catches engaging said cranks to move the valves in 30 one direction, means for tripping the catches for the return of the valves, sleeves *h* engaging the cranks to return the valves, and rocker *l* linked to said sleeves *h*, substantially as described. 35

43. The combination with valves *d* at opposite ends of the cylinder, of cranks connected to the valves, reciprocating members having catches engaging said cranks to move the valves in one direction, means for tripping the catches for the return of the valves, reciprocating members engaging the cranks to return the valves, and rocker *l* linked to said last-mentioned members, substantially as described. 40

In testimony whereof I have hereunto set my hand in the presence of two subscribing witnesses.

CHARLES C. WORTHINGTON.
